(57) **CLAIM**

The ornamental design for a ceiling fan blade, as shown and described.

DESCRIPTION

FIG. 1 is a top perspective view of a ceiling fan blade showing our new design;

FIG. 2 is a bottom perspective view thereof;

FIG. 3 is a top view thereof;

FIG. 4 is a bottom view thereof;

FIG. 5 is a rear view thereof, looking at a root of the ceiling fan blade;

FIG. 6 is a front view thereof, looking at a tip of the ceiling fan blade;

FIG. 7 is a left side view thereof;

FIG. 8 is a right side view thereof;

FIG. 9 is an enlarged view of the tip of the ceiling fan blade of FIG. 8; and,

FIG. 10 is an enlarged view of the root of the ceiling fan blade of FIG. 8.

Portions of the ceiling fan blade shown in broken lines form no part of the claimed design.
